DESIGN.

J. G. CHAPMAN.

EDGING.

APPLICATION FILED AUG. 2, 1919.

54,360.

Patented Jan. 20, 1920.

Inventor:

*John G. Chapman,
by his attorney,
Charles R. Searle.*

UNITED STATES PATENT OFFICE.

JOHN G. CHAPMAN, OF PORT WASHINGTON, NEW YORK, ASSIGNOR TO SANFORD NARROW FABRIC CO., OF NEW YORK, N. Y., A CORPORATION OF NEW YORK.

DESIGN FOR AN EDGING.

54,360.

Specification for Design.

Patented Jan. 20, 1920.

Application filed August 2, 1919. Serial No. 315,027. Term of patent 14 years.

To all whom it may concern:

Be it known that I, JOHN G. CHAPMAN, a citizen of the United States, residing at Port Washington, in the county of Nassau and State of New York, have invented a new, original, and ornamental Design for an Edging, of which the following is a specification, reference being had to the accompanying drawing, which shows a strip of edging embodying my new design in elevation.

I claim:

The ornamental design for an edging, as shown.

JOHN G. CHAPMAN.
